UNITED STATES PATENT OFFICE

MILDRED LEE, OF SANTA MONICA, CALIFORNIA

DESIGN FOR A TOY OR SIMILAR ARTICLE

Application filed March 10, 1931. Serial No. 39,020. Term of patent 8½ years.

To all whom it may concern:

Be it known that I, MILDRED LEE, a citizen of the United States, residing at Santa Monica, in the county of Los Angeles and State of California, have invented a new, original, and ornamental Design for a Toy or Similar Article, of which the following is a specification, reference being had to the accompanying drawings, forming a part thereof.

Fig. 2 is a view analogous to Fig. 1 showing the opposite side.

Fig. 3 is a front perspective view of the design shown in Fig. 1.

Fig. 4 is a rear perspective view of Fig. 1.

I claim:

The ornamental design for a toy or similar article, as shown.

Signed at Los Angeles, California, this 7 day of March, 1931.

MILDRED LEE.
